METHOD OF AND APPARATUS FOR FORGING UPSET ARTICLES

Application filed April 25, 1929. Serial No. 358,032.

This invention is concerned with improvements in machines designed for the plastic forming of metals by the application of heavy pressures, and more particularly the invention is set forth in its present form as an adaptation to forging machines of the upsetting and heading types.

In manufacturing processes where the metal is usually forged in a single stroke operation of a forming die, it is frequently necessary to provide some form of mechanism which will function to eject or kick the formed article from the die or forming head whereby the formed piece of metal will be ejected positively or removed from the forming cavities of the machine before a following blank is positioned in alignment therewith for a repeat of the forming operation. It frequently occurs that the ejection of the previously formed work from the forming dies necessitates the use of considerable force, this being particularly true in that class of upsetting or forming machines industrially utilizable in the formation of bolt heads and the heads of automotive valves. Since the shank of the bolt or valve stem is relatively slender compared to the bulk or mass of the metal formed in the head the ejecting means has usually comprised a slender rod of corresponding diameter which extended into a shank cavity of the forming die. Machines of this type usually embody a stationary frame part or anvil and a reciprocating head quite massive in design to withstand high compressive stresses without distorting and the head carries the forming die and due to the bulky design of the head it is necessary that the kicker or ejector rod be of considerable length, and particularly where articles are being formed having long shanks such as bolts and/or valves.

Wherefore the general object of the present invention is the provision of a novel ejector mechanism which can be utilized on various upsetting and header machines in an efficient manner regardless of the confining diameters of the valve shanks or bolts being manufactured or formed on the machine. The nature of the invention is such that the ejector mechanism may also function as part

of the work forming means, and accordingly my invention is directed also to the provision of an ejector mechanism which may be adapted to the present forms of upsetting and bolt heading machines in such manner that the ejector may comprise part of the die.

A further object of my invention is the provision of a novel ejector mechanism which may be substituted for a kicker or ejecting rod previously embodied in a valve header machine.

A still further object of my invention is the provision of a method of forming a single piece automotive valve member by a combined forging and extruding operation of the valve head and part of the valve stem whereby the valve body relative to the length of the valve stem will be accurately formed.

Other objects of my invention will herein-after be set forth in the following description which refers to the accompanying drawings illustrating two embodiments thereof.

In the drawings Fig. 1 is a plan view of a valve header machine equipped with my invention. Fig. 2 is a cross sectional side elevation taken through the header substantially along the line 2-2 of Fig. 1 and illustrating one form of my invention. Figs. 3 and 4 are fragmentary cross sectional elevations showing a modified form of my invention, and Fig. 5 is an enlarged cross sectional detail taken substantially along the line 5-5 of Fig. 4.

My invention contemplates the lateral supporting of a kicker or ejector rod, in a bolt header or valve header, at several places along the length of the rod whereby the heretofore encountered difficulty of preventing the rod from buckling when subjected to an unusual compressive load, due to the work sticking in the die forms is encountered will be readily overcome. By thus supporting the rod laterally at several points I am able to prevent the starting of the bend in the rod and, accordingly the rod is maintained as a uniformly loaded column when under load.

In Fig. 2 of the drawings, in cross section I show for the purpose of illustration and not in limitation thereof, my invention as applied generally to an upsetting machine

illustrated as being equipped with a stationary forming anvil 10, a die 11, the anvil 10 being rigidly mounted upon a heavy machine frame 13 and the forming die 11 being positioned within a head block 14. The head block 14 is usually mounted upon a slide or gate 15, the gate being reciprocated by a crank 16 through a connecting rod or pitman 17, the crank 16 being rotated by a source of power applied to gears or fly wheels 18 in any suitable manner.

The header machine illustrated in Figs. 1 and 2 and forming die 11 are particularly designed for the forming of a semi-formed valve head Va, on a shank Vb to produce a single piece automotive valve member; the semi-formed head portion Va being usually pre-formed or gathered to conform to the dot and dash shape shown in Fig. 3. The forming die 11 has a bore therein conforming to the diameter of the shank portion Vb of the valve and a removable sleeve 20, carried by the head block 14, may be considered as part of the forming die 11 in the present illustration.

In Fig. 2 I show an ejector rod 25 which in the usual installation is suspended on a suitable supporting medium attached to the machine frame in a position to clear the reciprocating movements of the slide 15. In the present instance, however, the ejector rod is supported by a series of annular bearing members 26 provided with different diameters and respectively disposed to move within a bore of varying diameter formed within a sleeve 30 concentrically arranged within the head block 14. The end 31 of the bore is of suitable diameter to slidably support the rear enlarged annular head end 33 of the ejector rod 25. The head 33 abuts a stop rod 35 of relatively large diameter compared to the diameter of the ejector rod 25 and the stop rod 35 may be supported by any suitable bridge work such as members 36 and 37 (see Figs. 1 and 2) secured to the machine frame at the end of a slideway formed therein to support the reciprocating slide member 15.

The operation of this arrangement is as follows: A work blank or valve stem having a preheated gathered head is inserted in the bore of the die member 11 when the slide 15 is moving forwardly from the right to the left in Figs. 1 and 2, (this operation usually being effected automatically) and as the crank 16 revolves to the left horizontal position the preheated head Va is forced against the anvil block 10, thus causing the hot gathered end of the valve stem Va to be compressed to the final valve head form. This operation causes some elongation of the valve stem portion Vb by an extruding action which takes place at the point E (see Fig. 2).

This extruding action will vary depending upon variations in the metallurgical conditions of the metal comprising the valve

body and the temperature thereof at the time of forming but the amount of extrusion in the present instance is limited by reason of the fact that the ejector kicker rod 25 is of sufficient length to have the forward end thereof disposed within the bore of the sleeve 20 to limit the extent of extrusion of the valve stem. Thus when a predetermined amount of extrusion of the stem causes the right end of the stem to abut the end of the ejector rod 25 any remaining surplus metal in the head portion Va of the valve will be caused to form a flash thereon about the perimeter of the valve head.

Upon the completion of this forging and extruding operation the kicker rod 25 acts to eject the valve stem from the bore of the die members 11 and 20, and as the sleeve 30 and annular bearing members 26 move to the right with the die block they are caused to gather when they contact with each other and the head 33 of the kicker rod. When the slide mechanism reciprocates from right to left these annular members are caused to be properly disposed longitudinally along the kicker rod as illustrated, by reason of the variation in their diameters and the variation of the diameter of the bore of the sleeve 30.

In Figs. 3, 4 and 5, I illustrate a modified and more refined manner of adapting my invention to valve headers of the present industrial type. In this construction the valve die 40 is removably mounted in a suitable counter bore formed in a head block 41, the head block being bored to receive a removable die liner or die extension sleeve 42 and die members 40 and 42 having aligned bores therein conforming to the diameter of the valve stem with only slight tolerance thereover. An extension 43 of the head block 41 is provided with an extension 44 in alignment with the die sleeve 42, whereby the several parts just described may be readily removably assembled within the slide 15 of the header illustrated in Fig. 2. The sleeve member illustrated in the construction, as shown in Fig. 3 in the present instance will comprise a sleeve member 50 having a bore of uniform diameter thereon to receive a series of small sleeve members 51, 52, 53, 54 and 55 of uniform outside diameter but of varying inside diameters, and which sleeve members coact with the annular members 51a, 52a, 53a, 54a respectively, and the head 55a of the kicker rod 56 to effect positioning of the members 51a, 52a, etc. I find this construction quite adaptable to the present day form of valve and bolt headers.

In this construction I also provide as shown in Fig. 5 a retaining means for each of the annular members 57a, etc., which may be in the form of ball members 60 disposed within a radial bore formed within each of the annular members and which are acted upon by a spring 61 retained within the radial bore

by any suitable means such as small screw members 62. The end of the kicker rod 56 adjacent the head 55a thereof is provided with suitably disposed grooves 58 (see Fig. 4) in which the ball members 60 will be forced to seat when the slide 15 is in the extreme left position (see Figs. 2 and 3), and as the slide 15 moves from the right to the left these annular members will be retained 6 in the collective position shown in Fig. 3 until the corresponding tapered shoulders on the sleeves 52, 53, etc. contact with the annular coni-form surfaces thereof, and when the slide has reached the extreme right position 10 the kicker rod 56 will be accurately laterally supported as shown in Fig. 4.

From the foregoing description of two adaptations of my invention it will be seen that I have provided a mechanism which is 20 simple in its mode of operation and is readily adaptable to the dimensional confines of the die blocks of header machines whereby it may be used in substitution of the present form of kicker rods and kicker mechanisms, and even 25 though the kicker rod is of relatively small diameter as compared to that of the required length thereof the rod nevertheless can be laterally supported at any desired number of longitudinal points whereby extreme compressive loads may be exerted upon the end 30 of the kicker rod without causing distortion thereof. It follows that I am thus utilizing the kicker rod as an end wall or an element of the forming die without causing distortion 35 and buckling of the kicker rod and I can therefore predetermine the amount of extrusion of the hot head metal into stem formation. This result overcomes a great deal 40 of material waste from the stem end of each valve piece when the ends are precision finished by a grinding operation.

It will be apparent also to those skilled in the art that the present form of my invention may be considerably varied to adapt the same 45 to various header constructions where work of shapes and contours quite different than bolts and automobile valves are being formed.

I claim:

1. In an apparatus of the character described, the combination of a reciprocating die head, an ejector member adapted to eject work pressed into a cavity formed in the die head, shiftable means for laterally supporting the ejector member when said member is subjected to working strains, and means for repositioning said shiftable means.

2. In a header machine, the combination of a movable cavitary die member having a bore extending therethrough, stationary work ejecting means extending into said bore, shiftable means for reinforcing the work ejecting means when the work ejecting means is caused to act upon the work in the cavity of said die, and means for repositioning said shiftable means.

3. In a header machine, a machine frame, a reciprocating metal forming mechanism, a die cooperating means supported by the frame of the machine, a stationary work ejector, shiftable means for laterally reinforcing the ejector when said die head is reciprocated toward the anvil of the machine whereby the ejector may constitute a work forming wall of the cavity of the die, and means for repositioning said shiftable means. 70

4. An apparatus of the character described comprising a reciprocating die head, a die carried thereby having an elongated cavity for the reception of a piece of work having a shank of substantially the same diameter as 80 said elongated cavity, means for reciprocating said die head, a stationary member associated with the reciprocating means to extend into said elongated cavity and a series of collectible bearing members for laterally 85 bracing said member during the forging stroke of said reciprocating means, and means for repositioning said collectible bearing members.

5. In an apparatus of the class described, 90 the combination of a die, a relatively thin member for ejecting work formed in the die, means for reinforcing said ejecting member against bending comprising a sleeve having a series of tapered shoulders of progressively 95 varying diameters, a corresponding number of collectible annular members adapted to engage said ejecting member and said shoulders, and spring means for retaining each of said annular members in collected position on said ejector member until each of said annular members is engaged by the corresponding shoulder of the sleeve. 100

In testimony whereof, I hereunto affix my signature.
